UNITED STATES PATENT OFFICE.

FRIEDEMAN R. JAEGER, OF OAK PARK, ILLINOIS.

MECHANICAL MOVEMENT.

1,252,698.

Specification of Letters Patent.

Patented Jan. 8, 1918.

Application filed June 30, 1915. Serial No. 37,135.

To all whom it may concern:

Be it known that I, FRIEDEMAN R. JAEGER, a citizen of the United States, residing at Oak Park, in the county of Cook and State 5 of Illinois, have invented certain new and useful Improvements in Mechanical Movements, of which the following is a specification.

My invention pertains to washing-machines in general, but relates more specifically, but not exclusively, to those appliances of this character having a rotary-drum adapted to contain the clothes to be washed, which is revolved alternately in opposite directions a predetermined number of times.

One of the objects of this invention is the provision of a washing appliance of this character wherein the door or doors of the drum will always be brought to a definite 20 accessible position whenever the movements of the drum are stopped, regardless of which direction of rotation of the latter has occurred just previously to such stopping.

A further aim of the invention is the provision in an appliance of this character facilitating the insertion of the drum in its casing and also its removal from such housing, the device being supplied with simple means for coupling and uncoupling the drum 30 to its operating-shaft.

Another purpose of the invention is the construction of the drum in such a manner as to facilitate the showering of water on the clothes contained therein during the 35 actuation of the drum.

The accomplishment of these and other objects of the invention will be appreciated by those skilled in this art from an understanding of the construction and operation 40 of a preferred embodiment of the same illustrated in the accompanying drawings forming a part of this specification and throughout the various views of which like reference characters refer to the same parts, together with the following detailed description 45 of such mechanism.

Referring to these drawings it will be observed that:

Figure 1 is an end elevation of the improved washing-machine;

Fig. 2 is an enlarged vertical section on line 2-2 of Fig. 1, the parts being viewed in the direction indicated by the arrows;

Fig. 3 is a vertical section on line 3-3

of Fig. 2 the parts being illustrated as 55 viewed from the direction indicated by the arrows;

Fig. 4 is a fragmentary perspective view of a portion of the bail or handle for the rotary drum;

Fig. 5 is a perspective view of the lower portion of the bearing receiving the trunnion of the drum;

Fig. 6 is an enlarged section on line 6-6 of Fig. 2;

Fig. 7 is a horizontal section on line 7-7 of Fig. 6;

Fig. 8 is an enlarged vertical section on line 8-8 of Fig. 2, and

Fig. 9 is a section on line 9-9 of Fig. 2.

Referring to the drawings, it will be observed that the appliance comprises a framework of suitable construction composed of a plurality of legs or posts 10, 10, equipped with casters or rollers 11, 11. These various legs are connected together by horizontal cross-bars 12, 13, 14, and 15, in any approved or suitable manner. The upper portion of the frame has mounted therein a fluid-tight casing 16 with a rounded or semi-cylindrical bottom 17, the upper edge of the casing being provided with a suitable flange-part 18 adapted to receive the marginal portions of a removable cover 19, all as is clearly illustrated in Figs. 2 and 3.

The inner face of one end-wall 20 of the casing or housing has mounted thereon an elongated, substantially U-shaped bearing-member 21, the upper portions of which are flat and are secured to the casing by screws 90 or bolts 22, 22. The middle and lower portion of this bent-bar is equipped with a flange 22 on the inner edge of the bar and at the bottom of the bearing-member such flange, which constitutes a bearing, is cut 95 away so as to provide a cam surface 23 clearly illustrated in Fig. 5.

The opposite end-wall 24 of the housing has a casing 25 mounted thereon, or rather secured by means of bolts 26, 26, to the cross-bars 13, 14. This smaller casing 25 has a bearing 27 (Fig. 2) for a short-shaft 28 which extends through the housing, and inside the latter it is provided on its end with a square socket 29 facing inwardly, the inclined upper-walls 30 and 31 of such socket being partially cut away, as is clearly shown in Fig. 2.

The clothes-receiving drum 32 is cylindrical in form and is desirably composed of sheet-metal provided with a plurality of perforations 33, 33. Such drum also has 5 two mating door-sections 34 and 35 hinged to the drum at 36 and 37, their adjoining edges being adapted to be clamped or held together by any suitable form of fastening-appliance 38. Inside, the drum has a plurality 10 of inwardly-projecting longitudinal gutters or channels 39 apertured at their inner portions at 40, the wall of the drum overlying such gutters being apertured at 41.

As the drum revolves and these gutters 15 are submerged in the water of the casing, they, of course, become filled with such liquid and during the continuance of their revolution, as they emerge from the water, they pour or shower their contents through 20 the apertures 40 on to the clothes in the drum, in this way aiding the cleansing operation. These gutters also act somewhat as distributors for the clothes in the drum, and, to a certain extent, perform the function 25 of rubbers.

This drum at one end, by means of a spider 42, has secured thereto an outstanding stub-shaft or trunnion 43, on which is mounted one arm 44 of a drum bail 45. The 30 lower end of arm 44 has an apertured hub or bearing 46 receiving the trunnion of the drum, and it also has two cam-lugs 47 and 48, the former being adapted to coöperate with the cam surface 23 and the latter 35 adapted to co-act with the edge of the flange or rib 22.

The opposite end of the rotary-drum has a spider 49 mounted thereon having an outstanding cylindrical-shaft 50 on which the 40 companion arm 51 of the bail is adapted to rock, and, outside of such arm, shaft 50 is equipped with a square or angular block or lug 52 adapted in the operative condition of the device to snugly and neatly fit inside 45 of the socket 29, so that the rotation of the latter will be transmitted through the part 52 to the drum containing the clothes.

The operation of this part of the appliance occurs substantially as follows:

50 Assuming that the drum has been removed from the housing for cleaning, that it is to be returned to the casing for the reception of soiled clothes to be cleaned, and that the drum doors 34 and 35 have been 55 closed and locked in such condition, the operator, by means of the bail 44, 45, 51 in an upright condition lowers the drum into the housing containing a suitable supply of soapy water. During this lowering the boss 60 46 slides down the passageway between the vertical portions of the flanges 22, 22, on to its lower curved supporting-end, and the square block 52 descends into the socket 29 by reason of the cut away portions of the 65 parts 30 and 31. Then the bail is swung

from its upright or vertical position into the inclined position shown in Fig. 3, and during this movement cam 47 co-acts with cam 23 and cam 48 coöperates with the edge of flange 22 so as to bodily push the 70 drum and its associated parts axially toward the wall 24, carrying the block 52 fully into the socket 29 so that all four of its edges will be housed within the four walls of such sockets. The drum or cage is now 75 ready to receive the clothes, which may be introduced by unlocking and opening the doors. Obviously, as the socket 29 is rotated the drum and its clothes will be likewise revolved, the bail, of course, remaining 80 stationary because of its pivotal engagement with the supports or trunnions of the drum.

The mechanical means for rotating the drum and reversing the direction of such rotation will now be described.

85 On the lower portion of the machine-frame, an electric motor 53 is mounted, and the rotation of its horizontal shaft is transmitted to the vertical shaft 54 by means of suitable gearing inclosed in the housing 55. The upper housing 56^a contains bevel gears, whereby the rotation of shaft 54 is transmitted to a shaft 56 accommodated in a casing 57. Inside of the boxing 25, shaft 56 loosely has mounted thereon the two bevel pinions 58 and 59 each equipped on its inner face with one element of a clutch-member characterized 60 and 61 respectively. These two bevel pinions are at all times in mesh with the teeth of a larger bevel gear 62 100 fixed to shaft 28. Between the gears 58 and 59 shaft 56 has a square portion 63, and slidable on this is a sleeve 64, the opposite ends of which are notched or toothed to constitute clutch elements 65, 66, adapted to 105 coöperate respectively with the members 60 and 61. If this sleeve is slid in one direction shaft 56 will rotate gear 62 in one direction through the clutch 65, 60, and the pinion 58. On the other hand, if the sleeve 110 is slid in the opposite direction, shaft 56 will rotate gear 62 in the opposite direction through the coöperating clutch-mechanism 66, 61, and the bevel-pinion 59.

In order to bring about such automatic 115 shifting, the device is provided with the following specified instrumentalities.

An arm 67 equipped at its upper end with a handle 68 is fulcrumed at 69 and its central portion is bowed or curved at 70 so as to 120 extend part way around a central portion of the sleeve 64 of reduced diameter, whereby by swinging of the arm will slide the sleeve on the part 63. Lever 67 has an arm 100 pivoted thereto at 101, such arm carrying a 125 rocking pin 72 through an aperture of which a rod 74 is adapted to slide slightly, the upper sharpened end of the rod rockingly fitting in a cavity 75 in the casing 25. A coil-expansion spring 76 surrounds rod 74 130

and bears at its opposite ends against the casing and pin 72. As is shown, lever 67 is slotted at 71 to permit the pin 72 to extend through the lever. Gear 62 is supplied 5 with a pin 77 normally spring-pushed toward the machine proper out of conflict with the pin 72, but capable of being advanced so that during the rotation of the gear 62 it will engage the pin 72 for a purpose hereinafter indicated.

The housing 25 also has pivotally mounted therein on a stud-shaft 80, a notched-wheel 78, the notches of which coöperate with a pin 79 on the rear face of the gear 15 62; the outer curved faces of the teeth of such notched element coöperating with the hub 62^a of gear 62, the face of such hub opposite the pin 79 being cut away at 62^b to permit turning of the notched-wheel 78, 20 these parts in effect constituting a Geneva movement. During each revolution of the gear 62 the pin 79 by co-action with the notched-wheel 78 turns the latter one-sixth of a revolution, rotation of the notched-wheel 25 at other times being prevented by its co-action with the hub 62^a. This notched-wheel 78 has as a part thereof or secured thereto a cam arm 81 adapted to coöperate with the depending tail 82 of a cam 83 pivoted at 84. Under ordinary circumstances 30 the arm 81 is out of contact with the tail 82 and the cam 83 by its own weight and the action of a depressing spring 83^a is down out of the path of travel of the spring-pressed pin 77. When, however, the gear 62 and the clothes-drum 32 have made six complete revolutions in one direction, the arm 81 will engage the tail 82 and swing the cam 83 up into the path of travel of the pin 77, 35 projecting the latter forwardly so that in its rotary travel it will engage the pin 72, swinging the latter to one side of the center of the lever 67, whereupon the expansion of the spring 76 will automatically shift the 40 arm 67 so as to disconnect one pair of clutch elements and clutch together the other pair, bringing about a quick reversal of rotation 45 of the gear 62 and the drum.

Then the drum and the gear will make six 50 complete revolutions in the opposite direction at the completion of which cam 83 will again be raised, projecting the pin 77 in such a position that during its travel it will shift the pin 72 to the opposite side of the lever 67, and bring about another quick reversal of the direction of rotation of the gear and drum, and this action will continue uninterruptedly until the operator wishes to stop it.

60 The top of the casing 25 is supplied with a curved rib 85 which has a central locking-notch 86 and the handle 68 is supplied with a spring-pressed locking-pin or rod 87 normally pressed downwardly by a spring 88 65 inside of the handle. This rod 87 has a lat-

eral or side pin 89 accommodated in a right-angle slot 90 of the handle.

During the ordinary operation of the device the pin 89 is lifted and pushed laterally into the horizontal portion of the slot 70 90, in this way holding the locking-rod 87 in retracted position. When it is desired to stop the movements of the machine, the operator merely swings the side pin 89 so as to bring it into register with the vertical portion of the slot 90, and since, under ordinary circumstances, the handle 68 will be at one side of the center, the rod 87 will remain on the part 85 and slide thereon until the handle is shifted to central position automatically, whereupon the freed locking-rod 87 descends into the notch 86 and locks the handle and arm 67 in vertical neutral position, both clutches then being inoperative so that the rotation of the gear 62 and drum immediately ceases.

To start the rotation of the drum, the operator lifts the side pin 89, turning it into the angle portion of the slot 90, and the arm 67 responding to the action of the spring 90 76 will render one or the other of the clutches operative and then the machine will continue in operation until stopped, that is, it will revolve the drum alternately six revolutions in opposite directions.

It should be noticed that the various parts of this mechanism are so constructed and arranged that the drum 32 will always stop with the doors 34, 35, uppermost, regardless of the direction of rotation of the drum just preceding its cessation of such movements. This is a novel feature which renders it unnecessary for the operator to pay any attention to the stopping of the drum, it being merely incumbent upon him to operate the finger or side pin 89 as described above and the machine will automatically do the rest. Movement of the drum beyond the desired position of rest is prevented by reason of the fact that the pin 77 cannot 105 pass the pin 72 which is held from further movement.

Having described this desirable embodiment of the invention, it will be clear to those skilled in this art that many minor 110 mechanical changes may be made in the structure presented without departure from the substance of the invention and without the sacrifice of any of its substantial benefits and advantages.

I claim:

1. In an appliance of the character described, the combination of a casing, a drum revoluble in said casing, means to revolve said drum automatically alternately in opposite directions a predetermined number of revolutions, including a clutch mechanism, a lever to shift said clutch mechanism, an arm pivoted on said lever, a rocking pin on said arm, a rod engaging said casing 125 130

and extended through an aperture of said arm, and a spring surrounding said rod and bearing against said pin, substantially as described.

5 2. In an appliance of the character described, the combination of a casing, a drum revoluble in said casing, means to revolve said drum automatically alternately in opposite directions a predetermined number of 10 revolutions, including a clutch mechanism, a lever to shift said clutch mechanism, an arm pivoted on said lever, a pin on said arm extended through a slot of said lever, a spring acting on said arm, and means to engage said pin to shift said lever under the 15 action of said spring, substantially as described.

3. In an appliance of the character described, the combination of a casing, a drum 20 revoluble in said casing, means to revolve said drum automatically alternately in opposite directions a predetermined number of revolutions, including a clutch mechanism, a lever to shift said clutch mechanism, an 25 arm pivoted on said lever, a rocking pin on said arm extended through a slot of said lever, a rod engaging said casing and projecting through an aperture of said pin, a

spring surrounding said rod and bearing against said pin, and means to engage said pin to shift the lever through the action of said spring, substantially as described.

4. In an appliance of the character described, the combination of a casing, a drum revoluble in said casing, means to revolve 35 said drum alternately in opposite directions a predetermined number of revolutions, and means to stop the drum positively in a predetermined position regardless of the immediate preceding direction of rotation, substantially as described.

5. In an appliance of the character described, the combination of a casing, a drum revoluble in said casing, means to revolve 40 said drum alternately in opposite directions a predetermined number of revolutions, and manually-controlled means to automatically stop the drum positively in a predetermined position regardless of the immediate preceding direction of rotation, substantially as 45 described.

FRIEDEMAN R. JAEGER.
